UNITED STATES PATENT OFFICE.

PAUL F. WILLIAMS, OF CHICAGO, ILLINOIS, ASSIGNOR TO G & W ELECTRIC SPECIALTY CO., OF CHICAGO, ILLINOIS, A CORPORATION OF ILLINOIS.

POTHEAD.

1,228,155.

Specification of Letters Patent.

Patented May 29, 1917.

Application filed May 13, 1908, Serial No. 432,728. Renewed September 18, 1912. Serial No. 721,098.

To all whom it may concern:

Be it known that I, PAUL F. WILLIAMS, citizen of the United States, residing at Chicago, in the county of Cook and State of Illinois, have invented a certain new and useful Improvement in Potheads, of which the following is a full, clear, concise, and exact description, reference being had to the accompanying drawings, forming a part of this specification.

My invention relates to terminals for electric cables or conductors, commonly called "pot heads". The principal object is to provide a simple, practical and effective device of this kind for terminating a cable, having a plurality of members, strands or conductors, and arranging for the leading out of the different members, strands or conductors separately or individually. To such end, I provide a structure, having a casing with an opening at one end to receive a single cable, or several cables bunched or grouped together, and at the other end with a plurality of outlets for the several cables, strands or conductors to be taken out separately. The casing is preferably provided with removable members, by which access can be gained to its interior, and the individual outlets are also desirably provided with removable parts or sections for convenience of access to their interior.

In the accompanying drawings, Figure 1 is a perspective view of a pot head, embodying my present invention. Fig. 2 is a vertical section of the same. Fig. 3 is a vertical section of one of the outlets of the device. Figs. 4 and 5 are cross-sectional views of the same, taken on lines 4-4 and 5-5 in Fig. 3. Fig. 6 is a vertical section of a modification, and Fig. 7 is a cross-section taken on line 7-7 in Fig. 6.

Referring first to the device shown in Figs. 1 to 4 inclusive, I show a casing 1, which may be made of insulating material, or metal, as desired, having a converging bottom, 2, provided with a tubular portion 3, serving as an inlet for a cable 4. A lid 5 is fitted upon the upper open end of the casing 1. This lid is bodily removable from the casing, and is provided with a plurality of outlets for the different members, strands or conductors of the cable, or for different cables. In the drawings, I have shown three such outlets, 6, although, of course,

the number could be varied. These outlets 55 6, 6 are secured firmly to the lid 5, as for example, by making them integral therewith, and are provided with removable caps 7, 7. Within the outlets are connecting devices conveniently consisting of cable terminals 8, 8 and conductor terminals 9, 9, whereof each terminal 8 consists of a plug shaped device, having a socket at each end, the upper one for the terminal 9 and the lower one for the end of the cable 12. A 65 flat member or web 10 is fitted upon the terminal 8, the web having an aperture, through which the terminal can pass. The terminal 8 is provided with a couple of lugs, 8^a, 8^a, and the web 10 with a couple of corresponding apertures, whereby the terminals can be passed up from below, and then the web turned to lock the terminal in position, it being noted that the lower portion of the bore of the outlet 6 is slightly contracted to form a ledge, on which the web 10 rests. The terminal 9 has a plug member 11, adapted to enter the socket at the upper end of the member 8, and is also provided with a member 13, for engaging the conductor which is led out from the device. 75

The lower members 8, 8 are intended to fit removably in the outlet tubes 6, 6, whereas the upper members 9, 9 fit upon the removable caps 7, 7. The general form of 85 connector is illustrated and claimed in my Patent No. 831,815, dated Sept. 25th, 1906, the present construction having some improvements thereon. The interior of the tubes 6, 6 and also the interior of the casing 1 is filled with insulating material 14, of any suitable or desired kind, preferably an insulating compound. Thus the cable with its three strands, or conductors, or parts, is led into the casing 1, and then its members are separated and connected with the cable ends of the connecting devices, and then the cover is put on and the removable webs are put in and given quarter turns to lock the connecting devices in place. 90 95

The insulating compound is filled into the casing before the lid is put on, and into the outlets after the webs are put in and locked, before which, however, the bottoms of the tubes are closed by plugs of tape 6^a. Then 105 the caps 7-7 are placed in position. Connection is thus made with the different parts or members of the cable, and if at any time

it is desired to disconnect the same, the caps or any of them are removed. These caps can be removed and replaced as desired, to make any connection or disconnection.

5. In the device shown in Figs. 6 and 7, I provide a casing 1, having a contracted opening 3, for a cable, and having a lid or cover 5, the same as the device previously described. The outlet tubes 6, 6, however, do not contain the connecting devices shown in the said other construction, but instead of that the several cable members are run directly through the outlets, and caps, as shown in Fig. 5, the latter having straight bores of uniform diameter, as shown in said figure. Insulating material is filled into the casing and outlet tubes, the same as in the other construction.

It will be understood that changes and modifications can be made without departing from the spirit of the invention.

What I claim is:

1. A device of the class specified, comprising a casing having an inlet, a cover for the casing having a plurality of outlets, said outlets being tubular and each being provided with metallic connecting devices, caps for said outlets, said caps being arranged in connection with insulating material in the outlets, so as to hermetically seal the outlets and the terminals therein, and insulating material in said casing arranged to seal the cable entering said inlet and also sealing the adjacent ends of the outlets.

2. A device of the class specified, comprising a casing having an inlet adapted to receive a cable or conductor and containing insulating material to seal the cable in said inlet, a cover for the casing, said cover being provided with a plurality of tubular outlets, each containing connecting devices and also containing insulating material to seal the cable strands or conductors and the connecting devices in place, and caps covering said outlets and arranged to hermetically seal the same.

3. A device of the class specified comprising a casing having an inlet, a cover having a plurality of outlets, insulating material in said casing, each outlet provided with metallic terminals adapted for connection and disconnection by outside conductors, and caps fitted over the outer ends of said outlets and arranged to close the same.

4. A device of the class specified comprising a casing having an inlet, insulating material in the case, a cover provided with a plurality of outlets, each outlet consisting of a tubular member extended through the cover, so that one end is inside of the case and the other projects beyond the cover, metallic connecting devices in said outlets, insulating material also in the outlets, and caps covering the projecting ends of said outlets and closing the same.

5. A device of the class specified comprising a casing having insulating material within the casing, a cover provided with a plurality of outlets, each outlet consisting of a tube extended through the cover, so that one end is inside of the casing and the other end projects away from the cover, connecting devices within the outlets, each consisting of metallic plug and socket members, insulating compound in the outlets, and caps for the outlets.

6. The combination of a casing having an inlet, insulating material in the casing, a cover for the casing provided with an outlet consisting of a tubular member extending through the cover and having its inner end in the casing and its outer end projecting from the cover, connecting devices in said tubular member; insulating material also in the tubular member, and a cap for the same.

7. A device of the class specified comprising a casing having an inlet and containing insulating material, a cover having an outlet consisting of a tubular member, connecting devices in said outlet, said devices comprising metallic plug and socket members, insulating compound in the outlet, and a cap for the same.

8. In a device of the class specified, a connecting device comprising metallic terminals adapted to be fitted together, one of the same being confined in an outlet tube having a shelf; and a web having an aperture for said terminal, said terminal having side lugs, and the web having corresponding recesses.

9. A device of the class specified, comprising a casing having an inlet, a cover for the casing having a plurality of outlets, said outlets being tubular and each being provided with metallic connecting devices, caps for said outlets, connecting devices carried by said caps, said caps being arranged in connection with insulating material in the outlets so as to hermetically seal the outlets and the terminals therein, and insulating material in the casing arranged to seal the cable entering said inlet and also seal the adjacent ends of the outlets.

10. A cable terminal comprising a bowl, a cover therefor, an insulating tube projecting through said cover, and a removable cap for said tube, said tube and cap carrying co-operating parts of a two-part connecting device.

11. A device of the class specified, comprising a bowl or casing having its lower end provided with an inlet and its upper end provided with a plurality of outlet openings, tubular insulators arranged in said outlet openings and having their inner ends projecting into the interior of the bowl or casing and having their upper ends provided with water sheds, and their upper ends projecting above the top of the bowl.

- or casing, and connecting devices arranged within said tubular insulators.
12. A device of the class specified, comprising a bowl or casing having an inlet opening at its bottom and a plurality of outlet openings at its top, tubular insulators arranged in said outlet openings and having their outer ends provided with moisture protecting devices and connecting devices arranged within said tubular insulators, the outer ends of said insulators being closed except for an opening to permit connection with said connecting devices.
13. A device of the class specified, comprising a bowl or casing having its lower end provided with an inlet opening and its top provided with a plurality of tubular insulators projecting above the top of the bowl or casing and provided with conical water shedding devices, and electrical conductors led into the inlet opening and spread within the bowl or casing and extended individually through the tubular insulators and sealed therein.
14. A device of the class specified, comprising a bowl or casing having its lower end provided with an inlet opening and its top provided with a plurality of tubular insulators projecting above the top of the bowl or casing, electrical conductors led into the inlet opening and spread within the bowl or casing and extended individually through the tubular insulators and sealed therein, and insulating compound within the bowl or casing sealing the inlet opening and the entrances to the tubular insulators and holding the conductors in position.
15. A device of the class specified, comprising a bowl or casing having an inlet opening and a plurality of outlet openings, tubular insulators for the outlet openings, said insulators having their outer ends provided with water shed devices, means for connecting conductors entering the inlet with conductors passing out the outlet openings and means for sealing said connecting means within said tubular insulators.
16. A device of the class specified, comprising a bowl or casing having its lower end provided with an inlet opening and its upper end provided with a plurality of tubular insulators projecting above the top of the bowl or casing, and having their upper ends provided with outwardly and downwardly extending water shedding members, said insulators being open throughout their length to permit the conductors to be extended through the bowl and then through the insulators, and having their bores substantially the size of the conductors.
17. A device of the class specified, having a bowl or casing provided with outlet apertures in combination with tubular insulators arranged in said apertures and provided with conical water shedding devices and connecting devices confined and sealed in said insulators.
18. A device of the class specified, comprising a bowl or casing having one of its walls provided with tubular insulating members forming outlets, said insulating members projecting on opposite sides of said wall, and insulating material within the bowl or casing sealing the inner ends of said members, and laterally projecting water-shedding devices on the outer ends of said members.
19. A device of the class specified, comprising a casing having an inlet, a cover for the casing having a plurality of outlets, said outlets being tubular, caps for said outlets, said caps covering insulating material in the outlets, and insulating material in said casing arranged to seal the cable entering said inlet, and also sealing the adjacent ends of the outlets.
20. A device of the class specified, comprising a casing having an inlet, a cover having a plurality of upwardly extending outlets, and water shedding caps fitted over the upper ends of said outlets.
21. A device of the class specified, comprising a bowl or casing having an inlet and a tubular insulator forming an outlet, said insulator being provided with a water shedding device, and a connecting device within said tubular insulator.
22. A device of the class specified comprising a bowl or casing having a tubular insulator forming an outlet and a connecting device located in said insulator, the opposite ends of said insulator being closed except for connection to said connecting device, and containing insulating material hermetically sealing said connecting device.
23. The combination of a bowl or casing, a tubular insulating member forming an outlet from said bowl or casing, a connecting device located within said insulating member and completely inclosed thereby, said connecting device being smaller than the interior of said insulating member, whereby a space is formed between the connecting device and the inner wall of the tubular insulating member, and insulating cement within the tubular insulating member embedding said connecting device.
24. The combination of a bowl or casing, a tubular insulating member forming an outlet from said bowl or casing, a connecting device located within said insulating member and completely inclosed thereby, said connecting device being smaller than the interior of said insulating member, whereby a space is formed between the connecting device and the inner wall of the tubular insulating member, and insulating cement within the tubular insulating member embedding said connecting device.

said tubular insulating member consisting of a tubular sleeve secured to the wall of the bowl or casing and made open at its outer end and containing said insulating cement, and a closure covering the outer open end of said sleeve.

25. The combination of a bowl or casing, a tubular insulating member forming an outlet from said bowl or casing, a connecting device located within said insulating member and completely inclosed thereby, said connecting device being smaller than the interior of said insulating member, whereby a space is formed between the connecting device and the inner wall of the tubular insulating member and insulating cement within the tubular insulating member and embedding said connecting device, said tubular insulating member consisting of a tubular sleeve secured to the wall of the bowl or casing and made open at its outer end and containing said insulating cement, and a closure covering the outer open end of said sleeve, said closure being conical shaped and pointing outwardly.

26. A device of the class specified, comprising a bowl or casing having an inlet and a plurality of outlets, said outlets being formed by tubular insulators passing through the wall of the bowl or casing and having their outer ends provided with water shedding devices, and connecting devices within said tubular insulators.

27. A device of the class specified, comprising a bowl or casing having an inlet and a tubular outlet extending upwardly from the top of the bowl or casing and provided with a water shedding device above the joint between the bowl and insulator.

40 28. A device of the class specified, comprising a bowl or casing having an inlet and an upwardly extending tubular outlet, and means for protecting the upper end of the outlet from moisture.

45 29. A device of the class specified comprising a bowl having an inlet and a plurality of outlets projecting upwardly above the bowl and provided with upwardly pointed conical water shedding members.

50 30. A device of the class specified comprising a bowl having an inlet and a plurality of outlets projecting upwardly from the top of the bowl, said outlets having open bores adapted to fit line conductors and provided above the top of the bowl with

outwardly and downwardly flaring petticoats.

31. A device of the class specified comprising a bowl having its bottom provided with an inlet adapted to fit an incoming cable and a plurality of outlets projecting upwardly above the top of the bowl, said outlets having bores adapted to receive and fit line conductors and being provided above the bowl with outwardly and downwardly flaring petticoats.

32. A device of the class specified comprising a bowl provided with an inlet and a plurality of outlets projecting upwardly from the top of the bowl and provided above the bowl with outwardly and downwardly flaring water shedding members, in combination with conductors led into the bowl through the outlet thereof and separated within the bowl and led separately out through said outlets.

33. A device of the class specified comprising a bowl provided with an inlet and a plurality of outlets projecting upwardly from the top of the bowl and provided above the bowl with outwardly and downwardly flaring water shedding members, in combination with conductors led into the bowl through the outlet thereof and separated within the bowl and led separately out through said outlets, said outlets being of a size to fit said outgoing conductors.

34. A device of the class specified comprising a bowl having an inlet and a plurality of outlets projecting upwardly from the top of the bowl, said outlets being provided with downwardly and outwardly flaring water shedding members, and means for hermetically sealing conductors in said inlet and outlets.

35. A device of the class specified comprising a bowl having an inlet and a plurality of outlets made of insulating material, and connecting devices inclosed and sealed by insulating material within said outlets.

36. A device of the class specified comprising a bowl or casing having an inlet and a tubular upstanding outlet provided with a conically shaped water shedding member.

In witness whereof, I hereunto subscribe my name this 22d day of April, A. D. 1908.

PAUL F. WILLIAMS.
